UNITED STATES PATENT OFFICE.

PHILIP JACOB DIEHL, OF BUTLER, PENNSYLVANIA.

EGG BEATER.

Application filed April 2, 1923. Serial No. 629,468.

To all whom it may concern:

Be it known that I, PHILIP J. DIEHL, a citizen of the United States of America, and a resident of Butler, in the county of Butler 5 and State of Pennsylvania, have invented a new and Improved Egg Beater, of which the following is a description.

My invention relates to an egg beater so called and is particularly intended for embodiment in the beaters of cake mixing machines for mixing batter, icing, etc. The arms of the beater in the machines referred to not infrequently break off at their juncture with the head carrying the same and 10 by which the arms are attached to the revolving spindle of the machine.

The general object of my invention is to provide a beater improved with respect to the means for attaching the beater arms to 20 the head, whereby the danger of breakage is practically eliminated.

The stated object is retained by providing an attaching means for the beater arms characterized by resiliency, thus eliminating 25 the unyielding character of the ordinary head and preventing the arms breaking at the juncture with the head.

Reference is to be had to the accompanying drawings forming a part of this specification, it being understood that the drawings are merely illustrative of one example 30 of the invention.

Figure 1 is a side elevation of a beater embodying my invention;

35 Figure 2 is a transverse section as indicated by the line 2—2, Figure 1;

Figure 3 is a detail in vertical section on an enlarged scale, the section being taken through one of the plugs provided for lending resiliency to the head at each beater arm member.

In the illustrated example 10 indicates a head having a shank 11 formed with a socket 12 at its upper end to receive the usual drive 45 spindle of a known form of cake mixing machine. The beater arms 13 generally of known shape are secured to the head as follows: Said head 10 has a section 14 in the form of a separate annular member forming 50 the lower portion of said head. In the head section or annular member 14, an annular series of sockets 15 are produced and internally threaded. Each socket 15 receives

an elongated plug 16 preferably of leather or equivalent elastic material which is screwed 55 into place in the socket 15 to firmly hold the plug in place. The plug 16 has a vertical through-bore for the passage of the vertical upper end of a beater arm member. Coaxial with the bore in the plug 16 is a bore 17 60 in the top of the head member 14 so that the member of a beater arm 13 passes vertically through the plug 16 and through said bore 17 to the top of the head member 14. Above the head member 14 the member of the 65 beater arm 13 is upset as at 18 to prevent said beater arm member from pulling out of its position. The upset upper ends 18 of the beater arm members are accommodated in rounded recesses 20 in the under side of the 70 body of the head 10 directly above the separate annular member 14.

With the described construction the repeated flexure of the beater arms 13 at their juncture with the head will not cause a sharp 75 bending at given points on the beater arm adjacent the head. The plugs 16 constitute shock absorbers for the bending strains developed in the beater arms and yield sufficiently to prevent the bending of the beater 80 arms in a manner to crystallize the same adjacent the under side of the head. Thus, the life of the beater arms is greatly prolonged.

I would state in conclusion that while the 85 illustrated example constitutes a practical embodiment of my invention, I do not limit myself strictly to the exact details herein illustrated, since, manifestly, the same can be considerably varied without departure from the spirit of the invention as defined in the 90 appended claims.

Having thus described my invention, I 95 claim:

1. A beater of the class described comprising a head adapted to be driven, beater arms on said head, and means attaching said beater arms to the head, said attaching means including yielding material in said head through which material the beater arms pass into the head.

100 2. A beater of the class described including a head adapted to be driven, beater arms on said head, and plugs of yielding material in said head, through which plugs the upper ends of the said beater arms pass into the 105 head.

3. A beater of the class described including a head adapted to be driven, and beater arms carried by said head, the lower portion of which head is in the form of a member 5 separate from the body of the head; said separate member having internally threaded sockets at the under side thereof, and leather

plugs in said threaded sockets, the upper ends of said beater arms passing through said plugs and through the material of said 10 separate member above said plugs, the upper ends of said beater arms being upset at the top of said separate member.

PHILIP JACOB DIEHL.
